PHONOGRAPH-RECORD ARM MOUNTING

Robert M. Cain, Charlotte, Mich., assignor to Wilcox-Gay Corporation, Charlotte, Mich., a corporation of Michigan

Application June 14, 1946, Serial No. 676,777

6 Claims. (Cl. 274—23)

1

My present invention relates to phonographs and more particularly to a novel mounting for a record cutting arm which will facilitate the raising of the cutting arm out of engagement with a record blank on the turn table and which will facilitate lowering the cutting arm into engagement with the record blank, and also into engagement with driving means for the cutting arm.

My present invention is an improvement on prior Patent No. 2,351,948 assigned to the assignee of the present invention. My invention is designed to replace the specific mounting of the cutting arm shown in the said patent while, nevertheless, retaining the same type of lateral driving means for the cutting arm and the same type of mounting for the cartridge which carries the cutting stylus.

The cutting arm should be so arranged when disengaged from the record blank or the turn table that it will remain in the disengaged position without further attention, while it may readily, however, be returned to the engaged position.

Previously, it has been deemed necessary to rotate the cutting arm vertically through an arc of slightly more than 90° in order to ensure that the cutting arm will remain in the raised position. Also, this full rotation of the cutting arm to the vertical position has heretofore been thought necessary in order effectively to disengage the driven means for the cutting arm from its driving means.

The principal object of my invention is the mounting of the cutting arm or other tone arm of a phonograph in such a manner that it may be raised and be maintained in the raised position on upward rotation thereof through a relatively small arc of the order of 45° and less.

Another object of my invention is the arrangement of a cutting arm or other tone arm for a phonograph in such a manner that the driving means therefor may be readily disengaged on rotating the cutting arm vertically through a substantially smaller angle.

It will, of course, be obvious that my invention is equally applicable to the pick up arm of a phonograph in order to maintain the same in raised position when it is desired to disengage it from the turn table.

The foregoing and many other objects of my invention will become apparent in the following description and drawings in which:

Figure 1 is a side view partly in cross-section showing my novel cutting arm mounting with the cutting arm lowered.

2

Figure 2 is a view corresponding to that of Figure 1 showing the cutting arm raised.

Figure 3 is a cross-sectional view taken on line 3—3 looking in the direction of the arrows.

Referring now to the figures, the turn table mounting plate 10 of the phonograph is supported in any suitable manner in the top of the cabinet. Suitable drive mechanism, not shown, but having the form generally illustrated in prior Patent No. 2,351,948, drives the turn table 11 carrying the record blank 12. Rotation of the turn table 11 by its drive means causes the turn table 11 to rotate its spindle 13. Spindle 13 is connected to the gear box 14 beneath the mounting plate 10 and through the worm gear speed reducing element housed in the gear box 14 drives the elongated worm gear 15. The drive for the gear 15 is also as shown in the said prior Patent No. 2,351,948. Worm gear 15 is engaged by the knife edge pawl 16 on the end of the flexible member 17 secured in any suitable manner as by the rivets 18 to the feed arm 19.

The flexible member 17 has vertical compliance but is so attached to the feed arm 19 that it has no lateral compliance with respect thereto. Consequently, any movement imparted to the pawl 16 by rotation of the screw 15 will result in exactly corresponding movement of the feed arm 19. An adjusting screw 20 is mounted at the outer end 30 of the feed arm 19 and held in adjusted position by the lock nut 21 in order to adjust the position of pawl 16 so as to properly engage the screw 15.

The cutting arm 25 carries the cutting stylus 26 at one end and the said stylus is held in place in the cartridge not shown by the set screw 27.

The mounting of the stylus in the cutting arm and the arrangement of the cartridge in the cutting arm 25 is exactly like that shown in the said prior Patent No. 2,351,948; this arrangement is not specifically described herein since it forms no part of the present invention.

The rear end of the cutting arm is pivotally mounted by means of the bearings 30 on the side flanges 31 of the rotatable platform 32. Bearings 30 as shown are preferably needle bearings of a well-known type comprising an adjustable pointed screw 33, 33 threaded through appropriately threaded openings in the side flanges 35, 35 of the cutting arm 25 and entering into conical sockets indicated at 36, 36 of the side flanges 31 of the platform 32.

The cutting arm 25 is thus readily rotatable vertically with respect to the platform 32 but has no lateral compliance or movement with respect 55 to the platform 32.

When the cutting arm 25 is lowered, the position of the stylus 26 with respect to the record blank 12 on the turn table 11 may be roughly adjusted by adjusting the set screw 50 threaded into the forward end of the top of platform 32, the height of the set screw being maintained by the lock nut 51. The under-side of the cutting arm 25 rests on the set screw 50 thereby determining the degree to which the cutting arm 25 may be rotated downwardly about the bearings 30, thus providing a rough adjustment of the position and angle of the cutting stylus 26. This arrangement is also shown in the aforesaid prior Patent No. 2,351,948. Fine adjustment of the position and angle of the cutting stylus 26 may then be obtained by adjustment of cartridge which carries stylus or needle 26 also in accordance with the disclosure of the said prior Patent No. 2,351,948.

Platform 32 is secured in any suitable manner to the top of post 40 and is keyed thereto so that it is necessarily rotatable therewith. Post 40 extends through opening 41 in the journal 42 and opening 43 in the base plate 10, so that the post 40 extends beneath the base plate 10.

Feed arm 19 is rigidly secured to the post 40 so that the post 40 is necessarily rotatable in accordance with lateral movement of the feed arm 19. A compression spring 45 surrounds the post 40 and is captured between the under surface of the base plate 10 and the upper surface of the feed arm 19. Accordingly, the post 40 and feed arm 19 together with the platform 32 are biased downwardly to the position shown in Figure 1.

Each of the flanges 31 of the platform 32 is provided with a downward extension 55 having a substantially vertical surface 56 on either side of a portion of the journal 42. Each of the vertical edges 56 is also provided at its lower end with a recess 57 having the detent 58. The recess 57 is, as shown, spaced substantially forward of the vertical edge 56.

A U-shaped wire 60 having horizontal portion 61 and the leg portions 62, 62 is pivotally connected at its opposite ends at 63, 63 in opposite appropriate openings in the opposite flanges 35, 35 of the cutting arm 25. Each of the legs 62 of the U-shaped wire 60 forms a link.

As will be obvious from the drawings, the pivotal connection 63 is on the opposite side of the bearings 30 from the stylus 26. A toggle is thus formed having one imaginary link indicated by the dotted line 70 between bearings 30 and pivot 63 and having as its other link the leg 62 of the U-shaped wire 60. This toggle is formed on each side.

Pivot 63 is the knee pin of the toggle 70-62. The end pivot 30 of link 70 can move vertically with the post 40, but has no other movement.

When the cutting arm 25 is in the lowered position of Figure 1, the lower end pivot of link 62 is fixed by reason of the fact that the horizontal arm 61 of the U-shaped wire bears against the vertical surface 56 of the downwardly depending arm 55 of platform 32, and also by reason of the fact that the portion 61 of the wire rests on the upper surface of journal 42.

The link or leg 62 of the toggle 70-62 may thus rotate about the pivot thereby formed, while the pivot remains fixed; this pivot remains fixed as long as any portion of the vertical surface 56 is engaged by portion 61 of the U-shaped wire.

When, now, the forward end of the cutting arm 25 in the region of the stylus 26 is manually

engaged and lifted, the cutting arm 25 is rotated upwardly about the pivot 30 and the pivot 63 on the cutting arm is forced down. Pivot 63 must move in accordance with the rotational movement of the cutting arm 25.

The pivot formed by the meeting of horizontal legs 61 of the U-shaped wire, the upper surface of the journal 42 and the vertical surface 56 is a stationary pivot during the initial upward movement of the cutting arm 25. Therefore, with the outer lower pivot of leg 62 thus fixed and with the knee pin of the toggle 63 being forced down, the opposite outer pivot 30 of the toggle 63 must move upwardly. But this other pivot 30 is secured to the platform 32, which in turn is secured to the post 40 which is also secured to the feed arm 19. Consequently, the post 40, platform 32 and feed arm 19 must move up.

This upward movement disengages the pawl 16 from the worm 15 so that the cutting arm 25 is disconnected from its drive when it is raised.

As shown, it is necessary to raise the cutting arm 25 to an angle of not more than 45° of its original down position in order to disengage the cutting arm from its drive.

Previously, however, as shown in the aforesaid Patent No. 2,351,948, it was thought necessary to raise the cutting arm through slightly more than 90° in order to maintain the cutting arm in raised and disengaged position. In fact, as shown in the aforesaid patent, the cutting arm 25 was raised to a point where the units which corresponded to the toggle 70-62 broke through center so that the compression spring 45 could even assist in maintaining the cutting arm raised.

My present invention is designed so that it will be necessary only to raise the cutting arm 25 sufficiently to disengage the pawl 16 from the screw 15 and so that when thus disengaged, the cutting arm 25 will remain in raised position as shown in Figure 2. This is accomplished by the recessed surface 57 and the detent 58 in the vertical surface 56 of the dependent members 55 of the platform 32.

When, as shown in Figure 2, cutting arm 25 has been raised sufficiently to disengage pawl 16 from screw 15, the member 55 has been raised to a sufficient height so that the recess 57 moves opposite the horizontal leg 61 of the U-shaped wire. The outer pivot of the link 62 of the toggle 70-62 now shifts over to the left to the position defined by the intersection of surfaces 57 with the upper surface of journal 42. When this outer pivot of link 62 of the toggle 70-62 thus shifts over to the left, the cutting arm 25 now rises without further lifting the post 40, platform 32 or feed arm 19.

Further lifting of post 40 and feed arm 19 is no longer necessary since the disengagement of pawl 16 from screw 15 has already been obtained; so that the displacement to the left (with respect to Figures 1 and 2) of surface 57 from surface 56 determines the extent to which the cutting arm 25 will be further raised after the upward movement 32 of post 40 and feed arm 19 has stopped. The surface 57 may be displaced sufficiently from surface 56 to even permit movement of the cutting arm 25 to full vertical position without any further upward movement of feed arm 19, post 40 of platform 32.

The detent surface 58, if surface 57 is displaced sufficiently from surface 56, may be horizontal and thereby resist the compression spring 45 in its effort to return the elements to position of Figure 1. In order to avoid any undesired re-

turn of the elements from the position of Figure 2 to the position of Figure 1, the surface 58 may be made as a detent surface, as shown, so that the horizontal portion 61 of the U-shaped wire 60 snaps into the detent 58.

The compression spring 45 is so designed that by itself it cannot cause the horizontal portion 61 of the wire 60 to slide out of the detent and the arm 25 remains in the position of Figure 2. The compression spring 45 and the angle of the detent 58 is, however, so designed that downward manual pressure on the stylus end of the cutting arm 25 will cause the horizontal portion 61 of the U-shaped wire 60 to ride out of the detent, thus pulling the portion 61 of wire 60 toward the right and permitting the compression spring 45 to pull the post 40, platform 32 and feed arm 19.

By means of the foregoing, it is thus possible to design and dimension the elements to allow for the limited travel necessary for post 40 in order to effect complete disengagement. Previously, as in Patent No. 2,351,948, the screw 15 and feed arm 19 were placed sufficiently below the base plate 10 so that the feed arm 19 has full clearance to rise through the distance made necessary by the full 90° upward rotation of the cutting arm 25. Since the link 62 of the cutting arm 25 is now in effect disconnected from its pivot after a relatively small upward rotation of the cutting arm 25, the cutting arm 25 may be raised to any height and rotated through any arc while only the first 30° or so of upward rotation of the cutting arm actually results in raising the feed arm 19.

Accordingly, the post 40 may be made shorter and the screw 15 may be brought up closer to the under-side of the base plate since the feed arm 19 need not be raised to the same height. This provides for a more compact, better operating and less expensive structure.

Also, by the provision of the detent surface 58, the necessity for raising the cutting arm 25 through a full 90° arc in order to maintain it in the up position is obviated and the cutting arm need merely be raised through an arc of 30° to 45° to be maintained in the up position. This makes it possible to provide a shallower well in the top of the cabinet for the phonograph apparatus where it is desired that the cover be closed with the cutting arm 25 in the up position.

In the foregoing, I have described my invention solely in connection with a specific preferred embodiment thereof. Since many variations and modifications of my invention will now be obvious to those skilled in the art, I prefer to be bound not by the specific disclosures herein contained but only by the appended claims.

I claim:

1. In a phonograph, an arm; means at the front end of said arm for carrying a needle in a position substantially normal to said arm; a rotatable vertical post; a platform secured thereto; the rear end of said arm being pivotally connected to said platform; said arm being rotatable about said pivot from a substantially horizontal position to a position wherein the front end thereof is raised through a substantial angle; a portion of said rear end of said arm projecting beyond said pivot; a journal for said post; said post being rotatable angularly and slidably vertically in said journal; said journal having a horizontal surface; a downwardly extending projection from said platform; an edge of said projection intersecting the plane of the horizontal surface of said journal; a link connected at one end to the rear portion of the

arm extending beyond the pivot thereof; and, at the other end, bearing against the angle defined by said edge of said platform projection and the horizontal surface of the journal; raising the front end of said arm causing said link to exert downward pressure on said journal surface to raise said post.

2. In a phonograph, an arm; means at the front end of said arm for carrying a needle in a position substantially normal to said arm; a rotatable vertical post; a platform secured thereto; the rear end of said arm being pivotally connected to said platform; said arm being rotatable about said pivot from a substantially horizontal position to a position wherein the front end thereof is raised through a substantial angle; a portion of said rear end of said arm projecting beyond said pivot; a journal for said post; said post being rotatable angularly and slidably vertically in said journal; said journal having a horizontal surface; a downwardly extending projection from said platform; an edge of said projection intersecting the plane of the horizontal surface of said journal; a link connected at one end to the rear portion of the arm extending beyond the pivot thereof; and, at the other end, bearing against the angle defined by said edge of said platform projection and the horizontal surface of the journal; raising the front end of said arm causing said link to exert downward pressure on said journal surface to raise said post; said projection moving up as said post is raised; a recess in said edge of said projection; said link shifting its lower pivot laterally as said recess moves opposite the lower end thereof to permit said arm to be raised further while said post remains at the level reached thereby just before said recess was reached.

3. In a phonograph, an arm; means at the front end of said arm for carrying a needle in a position substantially normal to said arm; a rotatable vertical post; a platform secured thereto; the rear end of said arm being pivotally connected to said platform; said arm being rotatable about said pivot from a substantially horizontal position to a position wherein the front end thereof is raised through a substantial angle; a portion of said rear end of said arm projecting beyond said pivot; a journal for said post; said post being rotatable angularly and slidably vertically in said journal; said journal having a horizontal surface; a downwardly extending projection from said platform; an edge of said projection intersecting the plane of the horizontal surface of said journal; a link connected at one end to the rear portion of the arm extending beyond the pivot thereof; and, at the other end, bearing against the angle defined by said edge of said platform projection and the horizontal surface of the journal; raising the front end of said arm causing said link to exert downward pressure on said journal surface to raise said post; said projection moving up as said post is raised; a recess in said edge of said projection; said link shifting its lower pivot laterally as said recess moves opposite the lower end thereof to permit said arm to be raised further while said post remains at the level reached thereby just before said recess was reached; means biasing said post downwardly; a detent in said recess engaging the end of said link and maintaining said arm in lifted position against the force of said biasing means.

4. In a phonograph, an arm; means at the front end of said arm for carrying a needle in

a position substantially normal to said arm; a rotatable vertical post; the rear end of said arm being pivotally connected to said post; said arm being rotatable about said pivot from a substantially horizontal position to a position wherein the front end thereof is raised through a substantial angle; a portion of said rear end of said arm projecting beyond said pivot; a journal for said post; said post being rotatable angularly and slideable vertically in said journal; said journal having a horizontal surface; the upper end of said post having a member secured thereto extending therefrom toward the front of the arm; said member having a downwardly extending projection intersecting the plane of the horizontal surface of said journal; a link connected at one end to the rear portion of the arm extending beyond the pivot thereof, and, at the other end, bearing against the angle defined by the edge of said projection and the horizontal surface of said journal; raising the front end of said arm causing said link to exert downward pressure on said journal surface to raise said post.

5. In a phonograph, an arm; means at the front end of said arm for carrying a needle in a position substantially normal to said arm; a rotatable vertical post; the rear end of said arm being pivotally connected to said post; said arm being rotatable about said pivot from a substantially horizontal position to a position wherein the front end thereof is raised through a substantial angle; a portion of said rear end of said arm projecting beyond said pivot; a journal for said post; said post being rotatable angularly and slideable vertically in said journal; said journal having a horizontal surface; the upper end of said post having a member secured thereto extending therefrom toward the front of the arm; said member having a downwardly extending projection intersecting the plane of the horizontal surface of said journal; a link connected at one end to the rear portion of the arm extending beyond the pivot thereof, and, at the other end, bearing against the angle defined by the edge of said projection and the horizontal surface of said journal; raising the front end of said arm causing said link to exert downward pressure on said journal surface to raise said post; said projection moving up as said post is raised; a recess in said edge of said projection;

said link shifting its lower pivot laterally as said recess moves opposite the lower end thereof to permit said arm to be raised further while said post remains at the level reached thereby just before said recess was reached.

5. In a phonograph, an arm; means at the front end of said arm for carrying a needle in a position substantially normal to said arm; a rotatable vertical post; the rear end of said arm being pivotally connected to said post; said arm being rotatable about said pivot from a substantially horizontal position to a position wherein the front end thereof is raised through a substantial angle; a portion of said rear end of said arm projecting beyond said pivot; a journal for said post; said post being rotatable angularly and slideable vertically in said journal; said journal having a horizontal surface; the upper end of said post having a member secured thereto extending therefrom toward the front of the arm; said member having a downwardly extending projection intersecting the plane of the horizontal surface of said journal; a link connected at one end to the rear portion of the arm extending beyond the pivot thereof, and, at the other end, bearing against the angle defined by the edge of said projection and the horizontal surface of said journal; raising the front end of said arm causing said link to exert downward pressure on said journal surface to raise said post; said projection moving up as said post is raised; a recess in said edge of said projection; said link shifting its lower pivot laterally as said recess moves opposite the lower end thereof to permit said arm to be raised further while said post remains at the level reached thereby just before said recess was reached; means biasing said post downwardly; a detent in said recess engaging the end of said link and maintaining said arm in lifted position against the force of said biasing means.
